UNITED STATES PATENT OFFICE

2,624,896

RUG SCRUBBING MACHINE

Kenneth C. Atkin, Muskegon, Mich., assignor to
 Clarke Sanding Machine Company, Muskegon,
 Mich., a corporation of Michigan

Application September 13, 1948, Serial No. 49,000

3. Claims. (Cl. 15—50)

1

This disclosure relates to a rug scrubbing machine of the type adapted to shampoo rugs on a floor surface, and it is the general aim of the invention to provide a machine having a novel support and adjusting means for the scrubbing brush so that the brush is not only held in the precise manner determined to accomplish the most efficient cleansing of the rug but is also so held as to avoid the tendency of prior machines to move over the surface of the rug in an uncontrolled manner as a result of the friction between the brush and the rug.

A specific object of the invention is to accomplish the foregoing result in a rug scrubbing machine adapted to utilize a single, flat rotary scrubbing brush, yet maintain the brush in a stable mounting so designed as to avoid the tendency to creep or wander when in use.

A further object of the invention is the provision of a rug scrubbing machine having a single flat, rotary scrubbing brush, together with means to adjust the working pressure of the brush and the angle of its axis of rotation to suit the machine to operation on rugs having various thicknesses and textures of nap.

Another object of the invention is to provide, in a rug scrubbing machine, an adjustable mounting for a rotary brush and its driving motor whereby the brush may be supported above and in relatively light contact with the surface of the rug, yet wherein the degree of contact between the brush and rug may be controlled, regulated and limited in accordance with the depth of the nap of the rug so that the most efficient cleansing may be obtained under any of various conditions.

A still further object of the invention is the provision of a machine utilizing a main frame on which the scrubbing brush and its driving mechanism is mounted, the main frame being pivoted on and supported by a secondary frame or cradle, together with means for adjusting the relative angular positions of the main frame and cradle, so that the brush is held with its axis slightly inclined to bring one edge of the brush only into contact with the rug surface, but may be tilted more or less to achieve the precise working pressure determined to give the best results.

The inventive concept of these teachings will be described in connection with two different embodiments of the invention illustrated in the drawings of this specification. In the drawings:

Figure 1 is a plan view of a preferred embodiment of the invention;

Figure 2 is a side elevational view of the form of the invention shown in Figure 1;

2

Figure 3 is a plan view similar to Fig. 1 showing a slightly modified form of the invention; and

Figure 4 is a side elevational view of the form of the invention shown in Figure 3.

The machine comprises, in general, a main frame 10 which carries a revolving scrubbing brush 11, and a supporting frame or cradle 12 to suspend the main frame and brush above the floor. A motor housing 13 encloses a motor 100 and reduction gearing to rotate the brush, and the unit is ordinarily provided with an upwardly extending handle 14, the lower end of which terminates in a pair of spaced arms 15 pivoted to the frame on the studs 16. It is contemplated that a handle 14 may include a shampoo reservoir 17 and may be provided with a control valve 18 and actuating rod 19 to regulate the flow of liquid shampoo downwardly through a supply tube 20 to an injector fitting 21 in the top of the frame 10.

The liquid shampoo may be fed to the brush 11 in the usual manner, and a flexible skirt 22 extends downwardly from the frame 10 to surround the brush and confine the foam developed by the action of the brush on the rug.

It has been mentioned that it is one of the aims of the present invention to provide a mechanism wherein the rotary scrubbing brush 11 may be raised or lowered and its axis of rotation 23 tilted to a greater or lesser degree from the vertical, to attain the desired degree of contact between the brush and the rug surface. With the axis of rotation of the brush tilted, only one side of the brush is brought into contact with the rug, since it has been learned that a better scrubbing action is attained in this manner than with the entire surface of the brush in contact with the rug, yet the tendency of the machine to wander is overcome.

To this end the supporting cradle 12 is formed in generally U-shaped or horseshoe shape, as viewed from above, so that the main frame is between the forwardly extending arms 24 of the cradle. The cradle is provided with casters 25 on adjustable pivot spindles 26 to adjust the cradle to level position. The main frame 10 is supported within the cradle on a pair of trunnions 27 threaded into the opposite sides of a bracket 28 secured to the frame 10 by machine screws 29. The trunnions 27 are pivoted in bosses 30 in the opposite arms of the cradle, so that the main frame may swing downwardly on the trunnions to bring the forward edge of the brush against the floor surfaces. It is a feature of the present invention that the pivotal movement of

the frame with respect to the cradle be precisely controlled so that the brush may be set to the exact angle desired, however, and to this end an adjusting screw 31 is threaded through one arm of the cradle to control the pivotal movement of the parts. The screw 31 has a hand wheel 32 so that it may be adjusted by hand, and its lower end is grooved at 33 and fitted into a slot in an extension 34 of the trunnion bracket 28, so that movement of the screw upwardly raises the frame and brush, while downward movement of the screw allows the frame and brush to swing downwardly to any working angle desired.

In operation, it will be seen that the cradle 12 and its casters 25 will support the frame 10, the brush 11 and the motor housing 13. The screw 31 provides means for raising or lowering the main housing, however, so that the degree of contact between the brush 11 and the surface of the rug may be precisely regulated to the point where best results are obtained with a rug of any given characteristics of texture or thickness.

In the form of the invention illustrated in Figures 3 and 4 the adjusting screw is located in the center of the rear curve of the cradle rather than at one side. To this end the trunnion bracket 23 is formed with a rearwardly extending arm 35 in which a vertical adjusting screw 36 is threaded. The screw 36 has a hand wheel 37 at its upper end, and its lower end has a reduced neck and ball 38 held in a socket in the cradle by the plate 39.

The operation of the form of the invention is almost identical with the form shown in Figures 1 and 2, since the cradle 12 and its casters 25 still support the frame 10, the brush 11 and the motor housing 13 in the same manner, and the axis 23 of the brush can be tilted at any desired angle with respect to the floor by turning the screw 36 to raise or lower the main housing. Thus the degree of contact between the brush 11 and the surface of the rug may be precisely regulated by rotating the hand wheel 37.

From the foregoing it will be seen that by the teachings of this invention it is possible to utilize the recognized advantages of a single, flat, rotary type brush, yet to control the contact of the brush on the floor so effectively as to successfully overcome the difficulties of control heretofore encountered in machines of this type.

Moreover, the mechanism here disclosed accomplishes the desired result in a simple and straightforward manner, without undue multiplicity or complexity of parts, and by an arrangement wherein all the parts are so assembled and related that the entire unit is rugged yet attractive, and is well adapted to economical mass production methods of manufacture while at the same time suited to convenient and easy servicing assembly or repair.

Having thus described the invention, what I claim as new and desired to protect by United States Letters Patent is:

1. In a rug scrubbing machine, in combination, a main frame with a single generally flat circular scrubbing brush rotatably mounted below the frame, a motor, a motor housing adapted to enclose said motor for driving said brush, a cradle at least partially encircling said main frame, casters for supporting said cradle, a pair of spaced trunnions pivotally connecting said main frame to said cra-

dle on a substantially horizontal axis of rotation, and manually operated means for tilting said main frame and scrubbing brush thereon with reference to said cradle whereby the brush may be tilted and held in any desired tilted position with relation to a surface to be scrubbed, said tilting means comprising an extension forming a part of said main frame and screwthreaded means connecting said extension to said cradle whereby to cause relative movement between said main frame and brush and said cradle about the axis of said trunnions.

2. In a rug scrubbing machine, in combination, a main frame with a single generally flat circular scrubbing brush rotatably mounted below the frame, a motor, a motor housing adapted to enclose said motor for driving said brush, a cradle at least partially encircling said main frame, casters for supporting said cradle, a pair of spaced trunnions pivotally connecting said main frame to said cradle on a substantially horizontal axis of rotation, and manually operated means for tilting said main frame and scrubbing brush thereon with reference to said cradle whereby the brush may be tilted and held in any desired tilted position with relation to a surface to be scrubbed, said tilting means comprising an extension forming a part of said main frame and screwthreaded means connecting said extension to said cradle whereby to cause relative movement between said main frame and brush and said cradle about the axis of said trunnions, said screwthreaded means having a screwthreaded connection with said cradle.

3. In a rug scrubbing machine, in combination, a main frame with a single generally flat circular scrubbing brush rotatably mounted below the frame, a motor, a motor housing adapted to enclose said motor for driving said brush, a cradle at least partially encircling said main frame, casters for supporting said cradle, a pair of spaced trunnions pivotally connecting said main frame to said cradle on a substantially horizontal axis of rotation, and manually operated means for tilting said main frame and scrubbing brush thereon with reference to said cradle whereby the brush may be tilted and held in any desired tilted position with relation to a surface to be scrubbed, said tilting means comprising an extension forming a part of said main frame and screwthreaded means connecting said extension to said cradle whereby to cause relative movement between said main frame and brush and said cradle about the axis of said trunnions, said screwthreaded means having a screwthreaded connection with said extension.

KENNETH C. ATKIN.
